UNITED STATES PATENT OFFICE

148,253

DESIGN FOR A HANDBAG

Ludovico Reich, Buenos Aires, Argentina, assignor to Jack J. Fischer, New York, N. Y.

Application September 27, 1946, Serial No. 133,605

Term of patent 3½ years

(Cl. D87—3)

To all whom it may concern:

Be it known, that I, Ludovico Reich, a citizen of the Republic of Argentina, residing at Buenos Aires, in the Republic of Argentina, have invented a new, original, and ornamental Design for Handbag, of which the following is a specification, reference being had to the accompanying drawing, forming part thereof.

Fig. 1 is a top plan view of a handbag, showing my design.

Fig. 2 is an end elevational view of the handbag; and

Fig. 3 is a side elevation of the handbag.

I claim:

The ornamental design for a handbag, as shown.
LUDOVICO REICH.
